UNITED STATES PATENT OFFICE

NEWTON S. HILLYARD, OF ST. JOSEPH, MISSOURI

DESIGN FOR A BOOK COVER

Application filed October 12, 1931. Serial No. 41,373. Term of patent 14 years.

To all whom it may concern:

Be it known that I, NEWTON S. HILLYARD, a citizen of the United States, residing at St. Joseph, in the county of Buchanan and State of Missouri, have invented a new original, and ornamental Design for Book Cover, of which the following is a specification, reference being had to the accompanying drawing, forming part thereof.

The figure of the drawing is a perspective view of the book cover showing my new design, the back of the cover being plain.

I claim:

The ornamental design for a book cover, as shown and described.

NEWTON S. HILLYARD.
